United States Patent Office.

JAMES A. LEFORGE, OF DECATUR, ILLINOIS.

Letters Patent No. 99,448, dated February 1, 1870.

IMPROVEMENT IN SPRING-HOLDERS FOR WAGON-SEATS

The Schedule referred to in these Letters Patent and making part of the same.

I, JAMES A. LEFORGE, of Decatur, in the county of Macon, and State of Illinois, have invented a Self-Supporting Spring-Holder for Wagon-Seats, of which the following is a specification.

Nature and Objects of the Invention.

My invention relates to a means of holding the wooden springs, (for which it is intended,) in their place, to prevent slipping out, at the same time giving them a firm rest.

Description of the Accompanying Drawings.

Figure 1 is a perspective view of a wagon-seat, with the self-supporting spring-holder attached.

Figure 2 is a top plan of the holder, showing the dowel-holes in the ends of the springs, and the manner of fastening the whole to the bottom of the seat.

Figure 3 is a bottom plan of holder.

Figure 4 is an elevation of holder, showing the dowel in the same, and the manner of preserving the springs in their places.

General Description.

In fig. 1, the seat A is fastened to the holder B, by

means of bolts passing through the holes c c c c, as shown in figs. 2 and 3.

In fig. 2 are shown the dowel-holes D D D D, in the ends of the springs, which fit over the four corresponding dowels, one of which is shown in fig. 4, as E.

In fig. 4 is shown one of the dowels, E, by which the springs are held in their places, their ends, at the same time, abutting on each other, and the ends of the springs being bevelled, so that when the holder is bolted on the seat, the springs cannot be displaced, as an additional precaution to prevent slipping, as shown in fig. 2.

Claim.

I claim, as my invention—

The self-supporting spring-holder B, and the means of fastening the springs in the same, by means of the dowel E, substantially as and for the purpose hereinbefore set forth.

JAMES A. LEFORGE.
